UNITED STATES PATENT OFFICE.

JOHN R. GAMMETER, OF AKRON, OHIO, ASSIGNOR, BY MESNE ASSIGNMENTS, TO THE
B. F. GOODRICH COMPANY, A CORPORATION OF NEW YORK.

DESIGN FOR A TIRE-TREAD.

45,107.

Specification for Design.

Patented Jan. 6, 1914.

Application filed March 4, 1912. Serial No. 681,648. Term of patent 14 years.

To all whom it may concern:

Be it known that I, JOHN R. GAMMETER, a citizen of the United States, residing at Akron, in the county of Summit and State of Ohio, have invented a new, original, and ornamental Design for Tire-Treads, of which the following is a specification, reference being had to the accompanying drawings, forming part thereof.

In the drawings: Figure 1 is a perspective

view of the tread, and Fig. 2 a top plan view thereof.

I claim:

The ornamental design for a tire-tread, as shown.

JOHN R. GAMMETER.
